UNITED STATES PATENT OFFICE

GEORGE WASHINGTON DAVIS, OF CHICAGO, ILLINOIS, ASSIGNOR OF ONE-HALF TO
NORMAN E. BENSINGER, OF CHICAGO, ILLINOIS

PIPE, CIGAR, OR CIGARETTE HOLDER

Application filed March 21, 1931. Serial No. 524,282.

This invention relates to tobacco pipes, cigar and cigarette holders and particularly to devices for obviating accumulations of moisture therein.

Objects of this invention are to provide improved means for effectually preventing the passage of saliva and moisture from the smoker's mouth into the stem or holder bore, where it would promote the formation of a disagreeable tar-like substance; to provide a structure of this kind which will allow a free passage of smoke into the mouth of the smoker and keep the pipe clean and dry; and to provide a simple and inexpensive device of this kind that can readily be applied to existing pipes without requiring any change in the structure thereof.

A specific embodiment of this invention is shown in the accompanying drawing, in which:

Fig. 1 is a perspective view of a pipe in which the invention is applied in the form of an attachment to the stem.

Fig. 2 is a fragmentary enlarged vertical section taken longitudinally through the stem.

Fig. 3 is an enlarged end elevation of the stem.

Fig. 4 is an enlarged perspective detail of the plate which covers the bore at the outer end of the stem.

Fig. 5 is an enlarged sectional detail on the line 5—5 of Fig. 2.

In the form shown, the stem 1 may be of any ordinary or preferred designed and material, provided with a bore 2 and a bead 3 having applied to its outer end, and covering the bore 2, a plate 4 fastened to the stem 1 by means of lips 5 which embrace the bead 3.

The plate 4 which may be varied in shape to suit the design of the end of the stem 1 is shown with lips 5, so shaped as to embrace the bead 3 and securely hold said plate at the outer end of said stem 1. The plate also has tongues 6 which extend sideways to completely cover the outer end of the bore 2.

In the form shown, the plate 4 is located at a capillary distance 7 from the end of the stem 1 to allow a free passage for smoke and prevent the inflow of saliva. However, it is

within the scope of this invention to make the plate 4 of a resilient material in which case the tongues 6 when under suction would move slightly to allow the free emission of smoke and on release of suction return to a position against the end of said stem 1 to prevent the inflow of saliva.

Tightly surrounding stem 1 and extending over the lips 5 is a sleeve 8 which securely holds said lips 5 in position and provides a finished covering for said lips 5. Said sleeve 8 is applied to said stem 1 in the form of a tube which may be of celluloid shrunk to a tight fit around said stem 1 and over said lips 5. This may be accomplished by slipping a suitably dimensioned tube of celluloid over the stem and immersing the same in hot water to shrink it.

In the form shown, the pipe stem has a bore which terminates in a long and narrow slot 9, and the tongue 6 is so arranged as to overlie the ends of this slot.

In operation, the capillary space 7 between the plate 4 and stem 1 will allow the free passage of smoke and due to the viscous nature of saliva will prevent its inflow.

Although but one specific embodiment of this invention is herein shown and described, it will be understood that details of the construction shown may be altered or omitted without departing from the spirit of this invention as defined by the following claims:

I claim:

1. A device of the class described, comprising a bored stem having a plate covering the outer end of its bore to form a baffle and located at a capillary distance from the stem to emit smoke and to prevent saliva from entering the bore of said stem and a sleeve on said stem overlapping edges of said plate to hold said plate.

2. A device of the class described, comprising a bored stem, having a resiliently flexible plate covering the outer end of its bore to provide a baffle and located to emit smoke and to prevent saliva from entering the bore of said stem, and a sleeve on said stem overlapping edges of said plate to hold said plate.

3. A device of the class described, comprising a bored stem having at the outer end of

its bore a closure plate having resilient tongues disposed across the bore so as to emit smoke under suction and to prevent saliva from entering the bore.

5. 4. A device of the class described, comprising a bored stem, having a plate covering the outer end of its bore to provide a baffle and located to emit smoke and to prevent saliva from entering the bore of said stem, and
10 having outwardly extended lips fastened to the outer end of the stem.

5. A device of the class described, comprising a bored stem, having a plate covering the outer end of the bore and having outwardly extending lips fastened to the outer end of the stem and a sleeve on said stem overlapping said lips to securely hold said plate.

Signed at Chicago this 19th day of March
20 1931.

GEORGE WASHINGTON DAVIS.
